FORM-FITTING BRA-SLIP

Rosaria Sadye D'Amato, Jackson Heights, N. Y.

Application May 14, 1947, Serial No. 748,067

4 Claims. (Cl. 2—73)

1

This invention relates to a combination form-fitting brassière and slip, otherwise known as a bra-slip. A bra-slip is a foundation and undergarment whose upper portion is a brassière for molding and supporting the breasts and whose lower portion is a skirt dependent from the brassière, said brassière and skirt thus forming a single article of apparel which is designed to fit and conform to the contour or curves of the body, particularly the upper portion of the torso, thereby enhancing the modelled appearance of the outergarment agreeably to the dictates of modern style.

Slips are usually made of delicate materials which are relatively inelastic so that they are easily torn along the seams, particularly when the material is tailored on the straight. Close-fitting slips have been cut on the bias thereby using the stretch of the bias cut fabric to reduce the risk of tearing at the seams. A garment fabricated from sections of material cut on the bias, has a natural tendency if stretched, to sag, twist and ride up the figure. Moreover a bias-cut garment is difficult to launder because to prevent distortion of the material and therefore of the shape of the garment it is important to iron the fabric on the straight. A garment cut on the bias requires more material than a similar garment cut on the straight, hence garments cut on the bias are more costly to produce.

One object of this invention is a form-fitting slip which constitutes a foundation garment and has body control characteristics.

Another object is a form-fitting bra-slip which drapes the torso in superior fashion thus bringing out the best lines of the wearer.

Another object is a slip which can be slipped on over the shoulders and bust yet which is inherently torso form-fitting.

Another object is a form-fitting slip which is straight-cut in the front below the waistline to prevent riding, sagging or twisting.

Another object is a bra-slip which fits the contours of the torso properly, and hangs smoothly without visible seams or fullness or folds so that no ridges are created to mar the eye appearance of a closely-fitting outergarment.

Another object is to substantially reduce the risk of tearing the garment when by sitting or stooping the wearer substantially increases the strain across the seat of the garment.

Another object is a bra-slip having a one-piece skirt panel which is so cut as to eliminate side seams and which drapes the fabric at the center back in bias formation to provide sufficient give when the wearer stoops or sits.

2

Another object is to so utilize elastic material in the upper portion of the garment as to effect form-fitting of the garment in all movements of the wearer.

Another object is a fastenerless form-fitting bra-slip which can be readily removed.

Another object is the elimination of a separate brassière.

Another object is to so combine a brassière and slip in a single form-fitting garment as to eliminate the use of fasteners.

Another object is to so combine a brassière and slip as to visibly retain the form-fitting lines normally produced by the conventional brassière.

15 Another object is an improved form-fitting bra-slip which automatically accommodates itself to the contours of the body of the wearer and to the wearer's movements.

Another object is a form-fitting bra-slip which is simple in construction, pleasing in appearance, economical to manufacture and which always retains correct form-fitting position on the body with perfect comfort and freedom of movement to the wearer.

25 Other objects will appear from the detailed description which follows.

A particular feature of the invention is the employment of a straight-cut skirt panel which eliminates side seams and which is circled to form the skirt by merely seaming along the center back line on the bias. The terms "straight" and "straight-cut" as used herein, mean that the warp threads of the fabric from which the garment is made, are arranged longitudinally or transversely with respect to the length of the garment as distinguished from the so called "bias-cut" in which the warp threads are oblique to the length of the garment. The garment is so fashioned as to minimize any tendency to stretch lengthwise, to sag, to hike up, or to impair the form-fitting qualities of the garment.

35 Straight-cut material is employed in a unique manner to produce a torso-fitting garment which automatically accommodates itself to any changes in the contours of the body with perfect comfort and freedom of movement, and which can be slipped on or off with perfect ease.

In the drawings comprising four sheets of ten figures, numbered Figs. 1 to 10 inclusive, one practical embodiment of the invention is shown.

50 Fig. 1 is a front view of the bra-slip as modelled.

Fig. 2 is a rear view of the same;

55 Fig. 3 is a perspective view of the upper portion of the bra-slip form-fitted to a torso;

Fig. 4 is a front view of the same;
 Fig. 5 is a side view of the upper portion of the
 bra-slip form-fitted to a torso;
 Fig. 6 is a back view of the same;
 Figs. 7 and 8 show the patterns of the breast
 pocket sections;
 Fig. 9 shows the pattern of the elastic back
 panel; and
 Fig. 10 shows the pattern of the skirt panel.
 Like references designate corresponding parts

23 and 24 are united to the skirt 21 at the hoop
 line 46 by lines of stitching 54 and 55, with the
 upper center front point 31 of the upper section
 30 of skirt panel 26 adjoining the neck line
 37 of each breast pocket 23, 24; and the edges
 41 merge with and form a continuation of the
 straight back line 35, and in conjunction there-
 with, complete the armholes of the garment
 (Fig. 3).

Suitable shoulder straps 25—25 may be at-
 tached at spaced points to the upper edge 35 of
 the elastic back panel 22, and to the upper points
 of the breast pockets 23 and 24 to complete the
 bra-slip which will have the general appearance
 of the garment modelled in Figs. 1 and 2 of the
 drawings.

In cutting the panels or sections of the slip,
 patterns of the skirt panel 26 (Fig. 10), of the
 right breast pocket (Fig. 7) and of the left breast
 pocket (Fig. 8), are placed upon the piece of ma-
 terial from which the garment is to be cut, so
 that the patterns occupy the position with re-
 spect to the selvage edges of the material which
 they occupy with respect to the running edges
 of the drawing, in which position the arrow lines
 27 (Fig. 10) will be parallel with the warp
 threads of the woven material so that the panels,
 when cut out, will be straight-cut. The curved
 edge 28 will define the bottom hem line of the
 skirt panel 26 and the edges 29—29, are cut ob-
 liquely with respect to the selvage edges of the
 material. The skirt panel 26 is circled by
 bringing the right upper back and left upper
 back skirt seam points 47 and 48 together with
 the edges 29—29 in alignment, and the center
 back skirt seam 45 (Fig. 2), is formed by stitch-
 ing a line of stitches 51 through both plies of
 the circled material in spaced relation to the
 running edges 29—29 (Fig. 10).

The right breast pocket 23 may be formed by
 stitching the center edges 39 and 43 (Fig. 7) of
 the inner and outer breast sections 36 and 40 to
 form the center pocket seam 44 (Figs. 3 and 4).
 The left breast pocket 24 is similarly formed by
 sewing the corresponding center edges of the
 inner and outer left breast sections 36L and 40L
 (Fig. 8).

The back panel 22 (Fig. 9) is cut from a length
 of suitable elastic material, so that the back
 panel 22 will stretch in at least one direction,
 namely transversely. An elastic material adapt-
 ed to stretch both lengthwise and crosswise may
 also be used. The panel 22 is cut so that its
 edges 32 will correspond to the outer under
 breast curvatures of the left and right breasts,
 respectively. The upper edge of the panel 22
 may be cut straight and hemmed over with a
 line of stitching 52 to give a straight back line
 35 and the lower edge of the panel is cut on the
 line of a reverse curve to include the waist front
 portion 33 and the lower center back curva-
 ture 34.

The right breast pocket 23 is secured to the
 elastic back panel 22 by stitching the outer
 breast under curvature edge 42 of outer breast
 section 40 to the under breast curvature 32 of
 the back panel with a line of stitching 53. The
 edge of the outer breast section 40L of the left
 breast pocket 24 is similarly attached to the edge
 of the under breast curvature 32 (Fig. 9) to par-
 tially assemble the brassière portion of the gar-
 ment. The edges of the armholes 41 and of the
 neck line 37 may be hemmed over or otherwise
 suitably finished by lines of stitching 56 and 51.

To finish the garment assembly, the elastic
 back panel 22 and the breast pockets 23 and 24
 are so attached to the skirt 21 that: the lower
 center back curvature 34 and the waist front
 portions 33—33 of back panel 22 (Fig. 9) and
 the edges 38 of the right and left breast pockets

23 and 24 are united to the skirt 21 at the hoop
 line 46 by lines of stitching 54 and 55, with the
 upper center front point 31 of the upper section
 30 of skirt panel 26 adjoining the neck line
 37 of each breast pocket 23, 24; and the edges
 41 merge with and form a continuation of the
 straight back line 35, and in conjunction there-
 with, complete the armholes of the garment
 (Fig. 3).
 Suitable shoulder straps 25—25 may be at-
 tached at spaced points to the upper edge 35 of
 the elastic back panel 22, and to the upper points
 of the breast pockets 23 and 24 to complete the
 bra-slip which will have the general appearance
 of the garment modelled in Figs. 1 and 2 of the
 drawings.
 The under curvatures 38 and 42 in conjunc-
 tion correspond to the under curvature of the
 breast and the center pocket seam 44 will be in
 alignment with the vertical axis of the breast,
 so that when the shoulder straps 25 are cor-
 rectly adjusted, the breast pockets 23 and 24 will
 correctly support the breasts in the position of
 normal posture. The upper portion of the gar-
 ment from the back line 35 to a line substantially
 midway between the waistline and the approxi-
 mate hip line 50 should be smaller than the
 torso for which it is designed, so that the elastic
 back panel 22 will be stretched slightly and thus
 placed under sufficient tension to correctly sepa-
 rate the breast pockets 23 and 24 in the position
 of normal posture and to retain the upper sec-
 tion 30 of the skirt 21 form-fitted to the mid-
 riff when the garment is worn. The skirt 21 is
 thus form-fitted to the torso both above, at, and
 below, the waistline, to a line approximating the
 approximate hip line 50 (Fig. 6). The skirt 21
 drapes and flares outwardly and downwardly
 from the approximate hip line 50, to impart
 modish lines to the lower portion of the garment.

The lower extremity of the center back curva-
 ture 34 extends to the approximate position of
 the hip line 50, and the hoop line 46 encircles the
 body from the upper back skirt seam points 47
 and 48 which approximate the hip line passing
 upwardly around the waist and crossing the waist
 line in the region of the waist front portion
 33—33 (Figs. 4 and 5), and tapering to the point
 31 which is approximately one-inch above the
 horizontal axis of the breasts.

The opening in the garment defined by the
 hoop line 46—46, and the opening in the gar-
 ment at the approximate hip line 50, are pur-
 posefully designed to be slightly larger than the
 shoulder line 49 (Fig. 6), so that when the gar-
 ment is slipped on or off, each of the said open-
 ings will be large enough to pass over both the
 bust and the shoulder lines. The elastic back
 panel 22 will stretch sufficiently in a crosswise
 direction in the region of the waistline to per-
 mit the bra-slip to clear the bust and shoul-
 ders when slipped on or off.

The panel 26 (Fig. 10) is straight-cut as in-
 dicated by the lines 27 which represent the di-
 rection of weave of either the warp threads or
 the cross threads, dependent upon whether the
 skirt panel 26 is cut lengthwise or crosswise of
 the fabric. As the skirt panel 26 is substantially
 sector-shaped, the oblique edges 29—29 are cut
 on the bias, so that when the skirt panel 26 is
 circled and stitched at 51 to form the center
 back skirt seam 45, either the warp threads or
 the cross threads, as the case may be, are brought
 together in bias formation at the center back
 seam 51. By this construction, the front of the

skirt panel 26 is straight-cut while the rear of said panel, particularly in the region of the seat, is in bias formation, the warp or cross threads of the fabric diverging outwardly on either side of the center back skirt seam 45, in the form of an inverted V.

The direction of the warp or cross threads, as indicated by the lines 27, commencing in the region of the imaginary right and left side lines 58 and 59 gradually changes from a straight-cut to a bias-cut, and the extent of the bias increases in the direction of the oblique side edges 29 to effect a substantial bias formation at the center back skirt seam 45 particularly in the region of the seat where the garment is subjected to maximum transverse strain and substantial stretch of the fabric is therefore required.

Since the front of skirt 21 is straight-cut, it can not be distorted as by riding up or sagging in front, and since the fabric is draped at the center back skirt seam 45 in bias formation, the seat of the garment will stretch when subjected to transverse strain.

A bra-slip constructed in accordance with this invention is therefore not only a completely closed torso-fitting garment devoid of all fasteners, adapted to slip on and off freely, but is also so tailored as to possess all of the advantages of both a straight-cut and a bias-cut garment, without the disadvantages inherent in a garment which is cut either straight or on the bias.

By utilizing a skirt panel 26 cut from a single piece of material and circling said panel to form the skirt of the bra-slip, side seams in the skirt are entirely eliminated and the skirt 21 may be formed by joining the marginal edges 29 to form the center back skirt seam 45.

What is claimed is:

1. A bras-slip comprising an upper section and a skirt section, said upper section including adjoined breast pockets and a back panel of elastic material, the bottom edges of the lower halves of said breast pockets being continuously and divergently curved to correspond substantially to the curvature of the diverging basal lines of the lower portions of the breasts when normally positioned, said back panel having, a straight top edge, oppositely concavely curved side edges cut to conform to the curvature, and joined to the outer edges, of, said breast pockets, and a bottom edge merging with said side edges and curving inwardly and downwardly therefrom to form two balanced convex curves and two balanced concavo-convex S curves in continuation of said convex curves, said S curves merging together at the central back to define a centrally disposed inverted bell-shaped projection extending downwards to the region of the hip line, shoulder straps secured to the breast pockets and to the elastic back panel to complete said upper section, said skirt section being fashioned from one piece of material cut on the straight in front and having equally and oppositely biased upwardly converging side edges, said material being circled to bring said side edges together, said side edges being joined together to complete the skirt section and form the central rear vertical seam thereof, the upper edge of said circled skirt section forming the upper hoop line opening, said upper hoop line opening being curvilinear and defining an upwardly extending inverted-V-shaped front central skirt portion, two balanced convexo-concave S shaped side and back portions in continuation of said front central

portion, said back portions merging together at the rear seam to define an inverted bell-shaped recess in said skirt section extending to the region of the hip line thereof, the upper edge of the skirt section being secured to the bottom edge of the upper section so that the front central skirt portion registers between the adjoined breast pockets, the inverted bell-shaped projection of the back panel registers in the inverted bell-shaped recess in the skirt section, and the S shaped portions of the skirt section register with the oppositely curved S portions of the bottom edge of the elastic back panel to close said upper hoop line opening, said elastic back panel stretching crosswise when the garment is worn and in conjunction with the shoulder straps causing the pockets to uplift the breasts and retain them in normal postural position, and said back panel being further stretchable within its elastic limits to enlarge the garment in the region of the waist line sufficiently to allow the garment to clear the bust and shoulders when slipped on or off.

2. A bra-slip comprising a form fitting bodice, and a skirt depending from said bodice, said bodice including adjoined form fitting breast pockets and a back panel of elastic material, the bottom edges of the lower halves of said breast pockets being continuously and divergently curved to correspond substantially to the curvature of the diverging basal lines of the lower portions of the breasts when normally positioned, said back panel having a top edge, oppositely concavely curved side edges cut to conform to the curvature of the outer edges of said breast pockets, and two bottom edges, each bottom edge curving downwardly, then inwardly, then downwardly, then inwardly again, said bottom edges in conjunction thereby forming a centrally disposed inverted bell-shaped elastic tab, said side edges being joined to the outer edges of said breast pockets to circle said bodice, said elastic tab projecting down the center back of the bodice to the region of the hip line, the skirt being fashioned out of material cut on the straight in front with a curved bottom edge, upwardly and inwardly converging side edges lying on equal and opposite biases of the material, and upwardly and inwardly extending curved top edges, said top edges being shaped to correspond in reverse to the curvature of the bottom edge of the circled bodice, so that when said skirt material is circled to bring its side edges together to form a skirt and the central rear seam thereof, said top edge will include a centrally disposed inverted V-shaped frontal tab which registers between the breast pockets, an inverted bell-shaped recess aligned with the rear seam and extending to the region of the hip line for receiving said elastic tab, and other portions extending between said frontal tab and said recess which register with the remaining portions of the elastic bottom edge of said bodice, the edges of the skirt and bodice when thus mated being secured together to complete the bra-slip, said elastic back panel stretching crosswise, when the garment is worn, to mold the breast pockets to the figure and retain the breasts in normal postural position, and said back panel being further stretchable without exceeding its elastic limits to enlarge the bodice sufficiently to allow the garment to pass over the bust and shoulders.

3. In a bra-slip and in combination a pair of adjoined form fitting breast posturing pockets, an elastic back panel extending between the op-

positively disposed outer side edges of said pockets and secured thereto by a line of stitches to fashion a circled form fitting bodice, the diverging lower edges of said pockets and the bottom edge of said elastic back panel in conjunction forming the bottom edge of the bodice, said bottom edge defining oppositely disposed symmetrical curves, said curves being convex in front, crossing the waistline near the sides of the bodice, and then curving downwards to merge in the region of the hip line and form a centrally disposed elastic tab, a skirt fashioned out of one piece of material cut on the straight in front having upwardly converging side edges lying on equal and opposite biases of the material, said material being circled to bring said oppositely biased side edges into abutment, said side edges being joined together to form the central rear seam of the skirt and to complete the hoop line opening at the top edge thereof, the top edge of the skirt being shaped so that said hoop line opening corresponds in reverse to the shape of the bottom edge of the bodice, said top edge having an inverted V-shaped front central tab registering in the opening between the diverging lower edges of the pockets of the bodice, and a recess for receiving the elastic tab, the remaining portions of the top edge of the skirt also registering with the remaining portions of the elastic bottom edge of the bodice, said edges when thus arranged in cooperative registry being stitched together to complete the bra-slip, said elastic back panel stretching crosswise when the garment is worn to mold the torso to the bodice to effect normal postural position of the torso, and said back panel being further stretchable within the elastic limits of the elastic back panel to enlarge the garment in the region of the waistline to clear the bust and shoulders whenever the garment is slipped on or off.

4. In a bra-slip and in combination, a pair of adjoined breast posturing pockets, an elastic back panel extending between and secured to the oppositely disposed outer side edges of said pockets to fashion a circled form fitting bodice, the diverging lower edges of said pockets and the bottom edge of said elastic back panel in conjunction completing the hoop line opening at the bottom

5 edge of the bodice, said bottom edge defining oppositely disposed symmetrical curves, said curves being convex in the front of the bodice, concave at the sides of the bodice and then curving downwards to merge in the region of the hip line at the central back to form a centrally disposed elastic tab, a skirt fashioned out of one piece of material cut on the straight in front and having upwardly converging side edges lying on equal and opposite biases of the material, said material being circled to bring said oppositely biased side edges into abutment, said side edges being joined together to form the central rear seam of the skirt and to complete the hoop line opening at the top edge thereof, the top edge of the skirt being shaped so that the hoop line opening corresponds in reverse to the shape of the bottom edge of the bodice, so that the top edge of the skirt and the bottom edge of the bodice when brought together in position of alignment co-operate to provide a foundation for a joint, said edges when thus positioned being joined together to complete the bra-slip and form the hoop line opening of the garment, 15 said elastic back panel stretching crosswise when the garment is worn to mold the torso to the bodice and the bodice to variations in contour of the torso to make that portion of the garment above the hip line form fitting, and said elastic back panel being further stretchable within its elastic limits to enlarge the form fitting portion of the garment sufficiently to clear the bust and shoulders whenever the garment is slipped on or off.
